WALL ANCHORING DEVICE

Robert Maxwell James, Buffalo, N. Y.

Application March 29, 1949, Serial No. 84,063

5 Claims. (Cl. 72—105)

1

This invention relates generally to a new and improved method for adapting hardened plastic structures such as concrete forms and the like for architectural treatment. More particularly, the present invention contemplates the provision of an anchorage device which can be advantageously employed in connection with undercut and dovetailed niches or recesses formed in concrete surfaces.

An anchorage device constructed in accordance with the provisions of the present invention includes a shank member which may be formed in such a manner as to define suitable anchorage for supplementary construction materials used in connection with concrete walls or other forms of hardened plastic material.

In one useful embodiment, the shank takes the form of a strip of metal which defines a corrugated pattern along its length and a flattened apertured crown at one end.

A pair of bifurcated flukes, more specifically, a pair of members each having a flat apertured base and a pair of substantially triangular shaped arms extending away from said base on angularly disposed planes intersecting the plane of the base is provided for seating within an undercut dovetailed recess formed by a removable button-type core. The shank is then inserted between the opposing flat apertured base portions of the flukes and suitable fastening means may be passed through the flukes and the shank member to place the complete anchorage device in a locked-together firm assembly.

The arms of each of the aforementioned flukes are provided with an acutely inclined inner edge in order that the arms may develop a substantially conical shaped bearing surface for cooperative locking engagement with a correspondingly shaped dovetailed niche.

It will be apparent that when two flukes and a shank having the aforementioned characteristics are placed in firm assembly with one another, the conical bearing surface referred to will be defined by a plurality of radially spaced angularly inclined arm portions. Thus, after the flukes are placed in the undercut recess or niche and assembled with a cooperating shank member, the anchorage device will be firmly secured in the concrete and cannot be withdrawn therefrom.

If desired, the niche or recess may be subsequently filled with additional mortar, thereby embedding the flukes of the anchorage device in the concrete.

A concrete wall adapted in accordance with the

2

features of the present invention is thus admirably suited to firmly anchor brick-type masonry adjacent the wall. By arranging the niches or recesses in a predetermined staggered pattern, anchorage devices may be located so as to have their shank portions lie between successive layers of masonry.

The extending shank of the anchorage device may also be advantageously employed as a pipe hanger and, of course, may be readily adapted to anchor stone or support marble or slate slabs and other types of suitable finishing material in proximate firm relationship with a concrete structure.

15 It is, therefore, an object of this invention to provide a novel and improved method of adapting a concrete surface for architectural treatment.

Another object of this invention is to provide 20 a novel and improved anchorage device which may be used in connection with a flat concrete surface defining a cooperating dovetail undercut key-recess.

25 A further object of this invention is to provide an anchorage device made completely from simple stamped metal elements which are economical to manufacture and which may be used with great facility.

30 Yet another object of my invention is to provide a reliable method of anchoring finishing material to a concrete surface.

35 It is believed that the methods disclosed by the present invention will be most clearly understood from the description of the apparatus provided for practicing same.

Many other objects and advantages of the present invention will become manifest to those versed in the art through reference to the following detailed description and the accompanying 40 drawings in which:

Figure 1 is a plan view of a flexible disk-type key form used for forming undercut dovetail recesses in plastic aggregates such as concrete and the like;

45 Figure 2 is a fragmentary cross sectional view showing the key form of Figure 1 attached to the liner surface of a mold form and surrounded in molded proximity by a plastic aggregate such as concrete;

50 Figure 3 is a fragmentary cross sectional view, partly broken away, showing how the key form of Figure 1 may be simultaneously withdrawn from the hardened concrete when the mold form is stripped from the surface of the concrete;

Figure 4 is a fragmentary end elevational view

showing an anchorage device seated in an undercut recess formed by a disk-type key form illustrated in Figures 1, 2 and 3;

Figure 5 is a fragmentary cross sectional view, partly in section, and partly broken away showing the anchorage device of Figure 4 seated in the undercut dovetailed recess; and

Figure 6 is an exploded view of an anchorage device embodying the principles of my invention.

As shown on the drawings:

Figure 1 shows a flexible disk-type key form indicated generally by the reference numeral 10. The key form 10 is preferably made of a hard oil-resisting rubber material such as neoprene or the like. As shown on Figure 1, the upper face of the key form 10 is provided with a circular concave recess 11 and a plurality of radially spaced V-shaped grooves 12 alternately spaced between corresponding radial tongue portions 13.

As may more clearly be seen on Figure 2, the peripheral edge of the tongue 13 is appropriately curved and tapers inwardly to define a substantially skived peripheral edge 14 terminating in a lower circular lip 15.

The lower face of the key form 10 is characterized by a conical recess 16 developed by the angularly inclined walls extending inwardly away from the lip 15. The walls terminate in an annular recess 17 having a sharply turned radius which operates as a hinge area for pivotal and flexible movement of the lip 15 and tongues 13 thereabout.

A centrally disposed hub 18 depends into the conical recess 16 and away from the annular recess 17, and, by way of example, may be formed to define an integral suction cup portion 19 for placing the key form 10 in firm adherence to the liner surface of a mold form 20.

It may be noted that before being affixed to a mold form, the hub 18 of the key form 10 normally terminates short of the plane developed by the lip 15, but when pressed against the liner surface of a mold form 20, the lip 15 is resiliently distended so as to produce a tight sealing juncture with the liner surface, thereby precluding the entrance of cement leakage into the conical recess 16 and producing an additional suction effect which tends to maintain the key form 10 in firm relationship with the liner surface of the mold form 20.

It will also be apparent, that when the lip 15 is so distended, the formation of the concrete lip in the locale of the point of juncture between the key form 10 and the liner surface of the mold form 20 will not be sharpened to a point, thereby precluding the formation of a sharp, easily fractured concrete lip around the recess.

As may be seen in Figure 3, when the mold form 20 is stripped away from the surface of the hardened concrete C, the suction cup 19 will remain affixed to the liner surface of the mold form 20 and the lip 15 as well as the tongues 13 will pivotally hinge around the hinge area formed by the annular recess 17. The concave recess 11 will also aid in permitting the radial contraction of the key form 10, thus, the key form 10 may be easily withdrawn from the concrete.

As withdrawal is effected, the tongues 13 will be displaced radially through the tapered areas defined by the radially spaced grooves 12, thereby adding to the effectiveness and facility of withdrawing the key form 10 from the concrete simultaneously upon the stripping of the mold

form 20 away from the surface of the concrete.

After the key form 10 has been removed, the flat surface of the concrete C will be characterized by an undercut dovetail niche 21 having a plurality of radially spaced fins 22 corresponding to the configuration of the key form 10.

The fins 22 not only add a decorative effect to the niche or recess 21, but greatly enhance the strength characteristics of the niche inasmuch as the fins 22 serve as radially spaced supports for the lip surrounding the recess 21.

Turning now to Figure 6 an anchorage device indicated generally by the reference numeral 25 is shown as including a shank 26, a first fluke 27, a second fluke 28, a screw 29 and a nut 30.

The shank 26 is herein shown as comprising a body portion 26a defining a corrugated pattern along its length and a flattened crown portion 26b suitably apertured as at 26c. It should be understood, of course, that the shank of the instant anchorage device 25 could be widely varied to suit the particular purpose of the user. Although the corrugated body 26a of the instant shank 26 is ideally suited for anchoring masonry work adjacent a concrete wall or for anchoring stone and other building finishing materials, it will be readily evident to those versed in the art that other types of mechanical anchoring structures could be substituted for the shank 26 without departing from the essential spirit of this invention.

Each of the flukes 27, 28 are identical in construction. Thus, analogous reference characters will be applied to like parts.

It will be seen that the fluke 27 is essentially a bifurcated structure having a flat base portion 27a suitably apertured as at 27b and a pair of shaped arms 27c which extend away from the base 27a.

In this particular embodiment, the arms 27c are bent up from the base 27a so as to lie on angularly disposed planes which intersect the reference plane developed by the base 27a.

It will be noted that the inner edge 27d of each arm 27c is acutely inclined and tapers outwardly. Thus, when a fastening means such as a screw 29 is passed through the apertures 27b, 26c, and 28b, and is received by a nut 30, the opposing arms 27c, 28c of the flukes 27, 28 define a plurality of radially spaced angularly inclined reference points which substantially develop a conical bearing surface for cooperative locking engagement with the dovetailed niche or recess 21.

In Figures 4 and 5, the anchorage device 25 is shown positioned in a niche or recess 21.

It will be apparent that a particularly facile method of accomplishing such positioning is to selectively space a pair of flukes 27, 28 in back to back relationship with the angularly inclined edges 27d, 28d in bearing registry with the dovetailed lips of the recess 21. The shank 26 may then be inserted between the opposing base portions 27a, 28a and the various elements may be locked together by means of the screw 29 and the nut 30.

It will be noted that the crown 26b of the shank 26 does not completely underlie the opposing base portions 27a, 28a of the flukes 27, 28 and as may be seen on Figure 5, a small space is left between the opposing flukes 27, 28. The presence of this space is desirable inasmuch as it assists in distributing any anchorage loads which may be subsequently placed upon the anchorage device 25.

It will also be noted that the insertion of the crown portion 26b between the opposing base portions 27a, 28a for assembly with a single fastener permits a two way flexibility which tends to spread the load evenly through all four points of bearing engagement developed by the angularly inclined edges 27d, 28d of the arms 27c, 28c.

Although I have resorted to detail in description of my invention for the sake of clarity, it will be readily understood by those versed in the art that many modifications may be suggested without departing from the essential spirit of my invention.

I claim as my invention:

1. An anchorage device for architectural treatment of a concrete surface of the type having dovetailed key recesses therein comprising, in combination, a shank having an apertured crown, a first fluke on one side of said crown and a second fluke on the other side of said crown and fastening means holding said shank and said flukes in firm assembly, each of said flukes having a flat apertured base and a pair of substantially triangularly shaped arms extending away from said base on angularly disposed planes intersecting the plane of said base and together forming a wedge shape lock, the base portions of said triangularly shaped arms extending radially outwardly towards one end of the anchorage device.

2. An anchorage device for architectural treatment of a concrete surface of the type having dovetailed key recesses therein comprising, in combination, a shank having a corrugated body and a flat apertured crown, a first fluke on one side of said crown and a second fluke on the other side of said crown and fastening means holding said shank and said flukes in firm assembly, each of said flukes having a flat apertured base and a pair of substantially triangularly shaped arms extending away from said base, said arms having their inner edge acutely inclined to develop a substantially conical bearing surface for cooperative locking engagement with said dovetailed key recesses in said surface.

3. An anchorage device for architectural treatment of a concrete surface defining dovetailed key recesses comprising, in combination, a shank having a flat apertured crown, a first fluke on one side of said crown and a second fluke on the other side of said crown and fastening means

holding said shank and said flukes in firm assembly, each of said flukes having a flat apertured base engaging said crown and a pair of substantially triangularly shaped arms extending away from said base, said arms having their inner edge acutely inclined to develop a substantially conical bearing surface for cooperative locking engagement with said dovetailed niche, said conical bearing surface more specifically comprising a plurality of radially spaced angularly inclined edges on said arm portions.

4. An anchorage device for use with a concrete member of the type having an undercut dovetailed niche, comprising, a pair of bifurcated flukes, each of said flukes having arms forming a bearing engagement plane adapted to lie in parallel registry with the undercut lip of the niche in the concrete member, a shank having a body portion with an apertured crown, and screw fastening means engaging said apertured crown and locking said flukes to said shank, whereby said anchorage device may be firmly locked in the niche of the concrete member.

5. An anchorage device for use with a concrete member of the type having an undercut dovetailed niche in the surface thereof, comprising, a pair of locking members, each of said locking members having outwardly extending arm portions together with one another forming a bearing engagement plane adapted to lie in parallel registry with the undercut lip of the niche in the concrete member, a shank having a body portion with an apertured crown, and screw fastening means engaging said apertured crown and locking said locking members to said shank, whereby said anchorage device may be firmly locked in the niche of the concrete member.
